CLAIM

The ornamental design for a medical product storage device, as shown and described.

DESCRIPTION

FIG. 1 is a top perspective view of the medical product storage device showing our new and ornamental design;
FIG. 2 is a bottom perspective view thereof;
FIG. 3 is a front elevation view thereof;
FIG. 4 is a back elevation view thereof;
FIG. 5 is a side elevation view thereof;
FIG. 6 is an alternate side elevation view thereof;
FIG. 7 is a top plan view thereof; and,
FIG. 8 is a bottom plan view thereof.

The broken lines show portions of the article that form no part of the claimed design.

1 Claim, 8 Drawing Sheets---
